UNITED STATES PATENT OFFICE.

ELMER P. GOLDSMITH, OF NEWARK, NEW JERSEY, ASSIGNOR TO MILLER & GOLDSMITH, OF NEW YORK, N. Y., A FIRM CONSISTING OF WILLIAM G. MILLER AND ELMER P. GOLDSMITH.

NOVELTY HANDKERCHIEF PACKAGE.

Application filed February 26, 1926. Serial No. 90,816.

This invention relates to fancy goods and has particular reference to novelties in the nature of gift cards, greeting, place cards, or the like.

5 Among the objects of the invention is to provide a peculiarly neat and attractive handkerchief package, or one consisting of a flat holder or protector and a handkerchief or its equivalent held in substantially flat 10 form within or in close relation to said holder, the holder serving not only as a protector for keeping the handkerchief in neat and clean condition, but also as a carrier not only for the handkerchief but a name, message, 15 or greeting to accompany the handkerchief or other analogous gift.

With the foregoing and other objects in view the invention consists in the arrangement and combination of parts hereinafter 20 described and claimed, and while the invention is not restricted to the exact details of construction disclosed or suggested herein, still for the purpose of illustrating a practical embodiment thereof reference is 25 had to the accompanying drawings in which like reference characters designate the same parts in the several views, and in which—

Figure 1 is a plan view of a preferred embodiment of the invention.

30 Figs. 2 and 3 are vertical transverse sections of the same on the correspondingly numbered lines thereof.

Fig. 4 is an upper edge view as would be seen looking downward from the upper edge 35 of Fig. 1.

Referring now more specifically to the drawings I show my improved novelty handkerchief package as embodying a card-like holder 10 of substantially flat form but 40 shown as comprising two plies or flaps 10^a and 10^b, the former being in front and the latter at the rear or bottom of the package. As indicated this holder is formed preferably by folding the stock, in the nature of a 45 heavy sheet of cardboard or its equivalent, in the middle as shown at 11, leaving the ends and bottom open as shown at 12 and 13. The top edge or fold 11 is slotted, however, at 14 as shown best in Fig. 4.

50 The rear panel 10^b is preferably imperforate for best protection of the handkerchief

H, but the front panel 10^a is provided with a window 15 adjacent to one corner thereof.

The handkerchiefs H which I have manufactured and sold extensively made up in 55 these packages are each provided with an embroidered field h which registers when the package is assembled with said window so that the fancy embroidery is visible at the window and so presents a peculiar embellishment for the package, and, moreover, the stock of the front panel surrounding the embroidery field h constitutes a guard protecting the delicate embroidery from immediate contact not only of the handler's fingers, but 60 other objects. 65

The bulk of the handkerchief lies in substantially flat form within the holder or between the two panels, but for embellishment and attractiveness of appearance, portions 70 of the remaining parts of the handkerchief are draped upon or along the edges of the holder remote from the window 15 where they may be secured as by pinning, the pins passing through or into the holder. Also 75 a tip of the handkerchief T is threaded through the slot 14 and is draped gracefully over the upper corner portion of the holder adjacent to the window 15.

As premised above this device is suitable 80 not only for mailing as a neat and attractive gift or remembrance, but it may be employed as in the nature of a place card by writing the individual's name upon the face of the holder. 85

I claim:

1. The herein described handkerchief package comprising a holder composed of a plurality of plies of laminated material folded in flat form along a bending or hinge line, one panel thereof being provided with a window, a handkerchief extending between the plies and held in substantially flat form therebetween, the handkerchief having an ornamented portion visible through said window and protected by the margin thereof, the folded edge portion of the holder being provided with a slot through which a tip portion of the handkerchief is laced and whence it is draped downward toward said 95 window. 100

2. The herein described handkerchief

package comprising a holder composed of a plurality of plies of laminated material folded in flat form along a bending or hinge line, one panel thereof being provided with a window, a handkerchief extending between the plies and held in substantially flat form therebetween, the handkerchief having an ornamented portion visible through said

window and protected by the margin thereof, portions of the handkerchief being draped over the margins of the holder remote from the window and there fastened in substantially permanent position. ¹⁰

In testimony whereof I affix my signature.

ELMER P. GOLDSMITH.
